UNITED STATES PATENT OFFICE.

CYRUS HOYT HEILIG, OF YORK, PENNSYLVANIA.

LOOM.

1,280,461.

Specification of Letters Patent.

Patented Oct. 1, 1918.

Application filed March 15, 1918. Serial No. 222,718.

To all whom it may concern:

Be it known that I, CYRUS H. HEILIG, a citizen of the United States, residing at York, in the county of York and State of Pennsylvania, have invented certain new and useful Improvements in Looms; and I do hereby declare the following to be a full, clear, and exact description of the invention, such as will enable others skilled in the art 10 to which it appertains to make and use the same.

This invention relates to the manufacture of cloth.

The main object of the invention is to produce a cloth having great resisting properties when under high tension or strain and which will not rip or split, as will cloth made by ordinary methods, thus particularly adapting the cloth for aeroplanes, balloons, cotton belts, cotton duck, sail cloth canvas, rain cloth, tire cloth or for any other purpose which subjects the fabric to hard wear, to liability of being punctured or split and to constant strain.

25 A further object of the invention is to improve the construction of looms in sundry details hereinafter set forth.

The invention will first be described in the following specification, which should be 30 read in connection with the accompanying drawings illustrating one embodiment thereof, and will then be pointed out in the appended claims.

In said drawings:

35 Figure 1 is a plan view of a loom constructed to weave the cloth according to the invention.

Fig. 2 is a vertical section taken substantially on line 2—2 of Fig. 1, however, the 40 heddle supporting and operating means not being shown.

Fig. 3 is a transverse sectional view taken through the lay beams,

Fig. 4 is an enlarged detail perspective 45 of a modified form of supporting and adjusting means for the lay beam.

The invention involves a method of weaving cloth C and other fabric which broadly consists in laying and packing the pick or 50 weft threads of the fabric at an angle of approximately 45 degrees relatively to the warp threads thereof.

At the present time, it is contemplated to 55 carry out this method by arranging the usual lay beam of a loom at such an angle relative to the frame thereof as will permit the

shuttle to deposit the pick thread from selvage to selvage at an angle of 45 degrees relative to the warp threads, the pick being then packed at this angle by the usual reciprocating movement of the lay. Strain placed on any point of this fabric, thus made, will be distributed over an area of 60 45 degrees instead of placing the entire load on opposite threads or lines, as in cases of the warp and weft being at right angles. In 65 the event of this fabric being punctured, it will not rip or split, as will fabric made by the ordinary method, since it absolutely will not tear in straight lines and pressure 70 or strain adjacent the edges of the puncture will be spread at an angle over unbroken threads. In other words, fabric having its warp and weft threads at right angles will 75 split under pressure, because the pressure spreads or separates said threads in straight and perpendicular lines relative to both the warp and weft; whereas, in the fabric produced by this method, pressure tending to rip will be diverted from such straight and 80 perpendicular lines, by virtue of the position of the weft, against unbroken warp and weft threads, which on account of their angular relation interlock in such a manner as to resist splitting and to distribute the 85 pressure over the fabric. It has been found from experiment that any degree of angle above or below 45 degrees reduces the efficiency of the fabric, and with the pick or weft at this angle the fabric will resist 90 pressure, strain and ripping with maximum efficiency. This method of weaving permits aeroplane and balloon cloth of greater efficiency to be made from cheaper materials, as, for instance, from light weight mercerized cotton yarn, instead of from costly 95 linen and silk. Also, the fabric produced by this method sheds water more readily, especially when stretched taut, due to the diagonal ways or lanes formed by the weft 100 threads which drain the water toward the edges of the fabric.

To carry the present method in practice, a loom is provided, as illustrated in drawings, comprising the usual frame 1 having 105 a warp beam 2 and a cloth roll 3 rotatably mounted at opposite ends thereof and driven by any suitable source of power. The warp threads A pass from the warp beam 2 through the heddles 4 and 5, provided as 110 usual for alternately raising and lowering alternate threads so as to form a shed

through which the shuttle 6 carrying the weft B passes, and through the reed R, as is well understood in the art. The shuttle moves back and forth over the lay beam 7 which is arranged below the warp threads and mounted on the frame at an angle of 45 degrees relative thereto, or, in all events, at 45 degrees relative to the warp, in order that the shuttle will lay the weft at the said angle relative to the warp. The lay beam 7 is, as usual, provided with shuttle-boxes 8 at its opposite ends and has its top surface inclined or beveled rearwardly to provide, together with the reed R, a raceway for the shuttle 6 which is operated in the usual manner. At the end of each movement of the shuttle, the lay beam, which carries the reed R, is moved forward from its position shown in Figs. 1 and 2 to force up the weft, which has been laid, and to pack the fabric. The reed R is also positioned at an angle of 45 degrees relative to the warp so that upon operation of the lay the weft will be properly packed at the desired angle, the reed 25 consisting of a plurality of vertical reed blades 9 (Figs. 2 and 3) having enlarged ends receivable in the channel bar 10 and the groove 11 formed in the lay beam adjacent its rear edge. The channel bar 10 is positioned slightly above the lay beam 7 and is supported at its ends by legs 12 secured to the lay beam. The reed blades 9 are further retained in adjusted position and against removal by bolts 13 extended transversely through the channel and carrying thumb-nuts 14, which when screwed tightly on the bolts tend to draw the walls of the channel together to tightly grip the enlarged ends of the blades 9. These blades 40 are, preferably, of a flat formation and are arranged to have their transverse axes extend parallel with the warp threads A in order to eliminate undue chafing of the latter threads and to insure the proper packing of the weft B. The heddle harness 15 is suspended from a roller 16, see Fig. 1, positioned at the same angle of 45 degrees, or substantially so, to correspond with the position of the lay beam in order that the 45 shed of warp threads produced by the operation of the heddles, as understood in the art, will be properly provided adjacent the lay beam and co-extensive therewith.

In a loom of the present construction, the 50 warp threads at the rear of the lay 7 will, by virtue of their own weight, have more slack on one side than on the other, which will produce a finished fabric having a stretched or pulled effect. This is obviated by the 55 provision of a pair of slightly spaced superposed rollers 17 journaled on the frame 1 and spaced a suitable distance rearwardly of the heddles 4 and 5 and being positioned at an angle corresponding to that of the 60 heddles and lay beam, thus restricting the 65 rear extension of the shed and placing that portion of the threads forming shed, and which are in the immediate vicinity of the lay, under equal tension.

The lay beam 8 is slidably mounted for reciprocating movement between vertically adjustable upper and lower bearings 18 and 19, respectively, secured to the inner face of opposite sides of the frame 1. In the present embodiment, it is preferred to reciprocate the lay from a single driving shaft 20 journaled on the frame between said bearings at each end of lay beam and having gears 21 and 22 thereon adjacent each side of the frame. These gears 21 and 22 mesh with idler gears 23 and 24, respectively, which take their motion from opposite sides of the shaft 20 and in return mesh with the driven gears 25 and 26, respectively, which are positioned in back of the lay beam 7 and each connected thereto by pitman rods 27 and 28, respectively, the gears 23, 24, 25 and 26 being preferably journaled on stud shafts mounted in the sides of the frame 1. Thus, the lay will be reciprocated in its angular position when the shaft 19 is rotated, the lay actuating means here shown and described being devised to improve and simplify the heretofore complicated mechanism.

The bearings 18 and 19 each comprise a supporting block 29 secured to the sides of the frame 1 by bolts 30 and having the face thereof opposing the lay beveled or inclined with which the beveled face of a wedge 31 co-operates. The opposite face of the wedge 31 is flat to provide an even surface on which the lay beam directly bears and reciprocates. There may be provided, however, anti-friction means 32 between the lay and the wedges 31. The wedges 31 are retained in position by bolts 33 extending therefrom through elongated slots 34 in the supporting blocks 29, the bolts having nuts 35 on the extended ends thereof to secure the wedges in adjusted position. The adjustment of the wedges on the blocks 29 is effected by thumb-screws 36 threaded in a bracket 37 secured to the frame, the free end of the screw having a swiveled connection with the wedge. Obviously the lay is held firmly in position, while being entirely free for easy reciprocating movement. When it is desired to raise and lower the lay beam, for purposes well understood, the nuts 35 are first loosened and the thumb-screws 36 are then manipulated, and after this adjustment has been made the nuts 35 are again tightened.

In Fig. 4, is shown a modified embodiment of the bearings for the lay, which embodiment contemplates a single vertically adjustable bearing for each end of the lay, and comprises a supporting plate 38 secured to the frame by any means and having an inclined top surface upon which is slidably

mounted a block 39 having an inclined face coöperating with the inclined face of the plate 38. The block 39 has an elongated horizontal slot or groove 40 therein, which 5 slidably receives the angular bracket 41, shown in dotted line, secured to the underside of the lay beam, the slot 40 being provided with a ball race adapted to contain suitable anti-frictional members 42. The 10 block 39 is further provided with a groove 43, in which engages a retaining flange 44 on the supporting plate 38 to maintain the parts 38 and 39 from accidental displacement. The block 39 is rendered slidably 15 adjustable by a thumb screw or bolt 45 threaded in a bracket 46 secured to the frame near the block, the free end of the screw having a swiveled connection with the latter. Thus when it is desired to raise 20 or lower the lay beam, this may be done by a single adjustment of the screws 44, as is obvious, the elongated slot 40 permitting at all times the free and unobstructed reciprocation of the lay beam.

25 It is desirable and preferable that the weft threads should run through the warp from selvage to selvage at an angle of 45 degrees thereto, but in some cases a lesser angle of approximately 45 degrees may suffice.

30 Having described my method of making fabric and the preferred embodiment of the means I employ in practising the method, what I claim is:

35 1. The combination with a loom for weaving fabric having a weft diagonal to the warp, of means on the loom diagonal to the warp and acting thereon effecting an even tension on that portion of the warp-threads forming the shed.

40 2. The combination with a loom for weaving fabric having a weft diagonal to the warp, of heddle devices disposed diagonally to the warp, and means on the frame at the rear of the heddle devices, and extending

45 substantially parallel therewith and acting on the warp for effecting an even tension on that portion of the warp-threads forming the shed.

3. The combination with a loom for weaving a fabric having a weft diagonal to the 50 warp, of heddle devices arranged diagonally on the loom, and a pair of spaced superposed rollers mounted on the frame at the rear of the heddles and extending substantially parallel therewith, said warp-threads being 55 adapted to pass between said rollers to restrict the rearward extension of the shed and effect an even tension on that portion of said threads forming the shed.

4. The combination with a loom for weaving a fabric having a weft diagonal to the 60 warp, of rollers disposed diagonally to the warp and behind the lay for causing an even tension on the warp threads, thereby preventing the side portions of the finished 65 fabric from being stretched, or caused to sag.

5. In a loom for weaving a fabric having 70 weft threads extending diagonally to the warp, the combination with a frame and a lay arranged thereon diagonally relatively 75 to the warp, of a transverse shaft journaled in the frame below the lay, and having gears thereon adjacent to the sides of the frame, the gear on one side of frame lying behind an end of the lay, and the other gear lying 80 in front of the other end of the lay when the latter is in normal position, and gearing mounted on each side of frame, and meshing respectively with said first gears, and connected by pitman rods to the lay, said last 85 gearing on each side of the frame taking its motion on opposite sides of said shaft.

In testimony whereof I affix my signature in the presence of two witnesses.
